UNITED STATES PATENT OFFICE.

EDGAR KILNER, OF MANCHESTER, ENGLAND.

LOOM FOR WEAVING.

Application filed June 17, 1924, Serial No. 720,534, and in Great Britain June 28, 1923.

This invention relates to improvements connected with looms for weaving and consists in the arrangement and construction and application of a shuttleless weft delivery device for one or two looms coupled with slight necessary alteration to parts of existing looms when the apparatus is applied thereto. In some cases two looms and the wefting apparatus may form one unit.

10 It is well known that, in most looms and more particularly what are known as broad looms, the picking device for the shuttle, or weft guide, requires a considerable portion of the power used in driving a loom; in my 15 invention I entirely discard the picking device and arrange at one side of one loom, or between two adjacent looms, a traversing device adapted to pass across the running board first of one loom, and then the other, 20 which traversing device will be suitably driven and will carry at its ends, fingers or clips to pick up the end of the weft and carry it across the running board, leave it there, return and bring another end and so 25 on. When one end of a device for two looms is carrying the weft of one loom, the other end will be passing across the other loom running board to collect an end thread or pick. The traversing device may be one rod 30 to serve two looms alternately as before mentioned, or may comprise two rods one for each loom in which case it will be possible to cause the same to operate at different speeds, and so weave pieces of varying width 35 in each loom. No picking motion, and no weft guides operating by a picker, are required, but when the traversing device is operating across the running boards, the usual movable lay on batten must be arranged to 40 dwell. During the motion of the batten the traversing device will move with the same and be suitably operated to this end.

I make no claim for excessive speed as to 45 number of picks per minute but I may employ an endless weft and select or pick up any desired weft of a number. There is no delay in the running of the loom owing to shuttle changing and therefore the output 50 will be steady and consequently will equal with a slow pick loom the output of a fast loom. The whole apparatus may run with but little attention for a considerable time and it is particularly adaptable to what is known as the broad type of loom. There 55 will be but little waste of yarn, and the distance the yarn is carried by the traversing

fingers or the like may be varied. The power now required to drive one picker motion should be more than sufficient to drive the traversing weft feed motion for two 60 looms, therefore the saving effected on this operation alone will be considerable.

In describing my invention in detail reference is made to the accompanying sheets of drawings in which:—

65 Fig. 1 is a front elevation illustrating the application of my invention to two looms, the looms being shown in dotted lines;

Fig. 2 is a partly sectional side elevation taken approximately on line 2—2 of Fig. 1;

70 Fig. 3 is a detail side view of the mechanism for transmitting motion from one rack bar to the other;

Figs. 4 and 5 are detail side views of a 75 stop member hereinafter described;

Fig. 6 is a detail side view of another stop member forming part of the invention;

80 Figs. 7 and 8 are sectional plan views of a gripper device forming a part of the invention, the device being shown in different positions in the two figures, Fig. 8 showing also a fragment of fabric;

Fig. 9 is a front elevation of the gripper device shown in Figs. 7 and 8, the device being shown in all of these figures broken 85 away from the rack bar which carries it;

Fig. 10 is a cross-section taken approximately on the line 10—10 of Fig. 9;

Fig. 11 illustrates a development of a lead cylinder forming a part of the invention; 90 and

Fig. 12 is a sectional plan view illustrating in full and dotted lines respectively different positions of the gripper mechanism 95 relatively to the fabric being woven during the passage of the gripper mechanism from one side to the other of said fabric.

The same character of reference designates the same parts in the different figures of the drawings.

100 Referring to the drawings, a pair of looms designated generally by the reference characters L, L', are erected in longitudinal alinement with each other and spaced apart one from the other. Between the looms L, 105 L', is mounted for rotation a cylinder or drum C, the surface of which is provided with a pair of oppositely disposed lead grooves T, each of said grooves extending in the form of a V from one end of the 110 cylinder to the other and communicating at each end thereof with a groove T' encircling

the end of the cylinder, as shown in the development of the cylinder illustrated in Fig. 11. The cylinder is rotated by means of a gear C' which receives motion from any suitable source and is in mesh with a pinion C² carried by the cylinder. The points of communication between the lead grooves T and the grooves T' are each guarded by a pivoted switch gate T², the gate at one junction being pivotally connected by a rod T³ with the other gate at the same end of the cylinder whereby when one gate is open the other will be closed as shown in Fig. 11.

Supported for oscillatory movement on the shaft of cylinder C are a pair of standards or brackets B, one at each end of the cylinder, which brackets are adapted to be oscillated by a link connection B' from an eccentric B² carried by a shaft B³ (see Fig. 3). A similar pair of brackets B^x are pivotally mounted one at the outer end of each loom L, L'.

Supported on the brackets B, B^x and disposed above the cylinder C is an elongated table or slideway N, on which is mounted for reciprocatory motion a rack bar R' for reciprocation a rack bar R' which is provided with a depending stud S (see Fig. 2) that passes through a slot in the table N and engages the guide grooves T of the cylinder, whereby when the cylinder is rotated, owing to the engagement of its groove with the stud S the rack bar R' will be reciprocated on the slideway N, in a manner which will be readily understood.

Supported on the brackets B at a point above and to the rear of the slideway N is a second table or slideway N', on which is mounted for reciprocation a second rack bar R. Reciprocatory motion is transmitted to the rack bar R from the rack bar R', and for this purpose a frame A^x is secured to the brackets B (see Fig. 2) in which frame is mounted for rotation a horizontal shaft A⁶ having secured at one end thereof a gear A in mesh with the rack bar R' and at its opposite end a bevel gear A' in mesh with a bevel pinion A² mounted on a vertical shaft A⁸ supported in the frame A^x, the said vertical shaft also carrying a bevel gear A³ in mesh with a bevel pinion A⁴ secured at one end of a horizontal stud shaft A⁷ mounted for rotation in frame A^x, said stud shaft having at its opposite end a gear A⁵ in mesh with the rack bar R. It will thus be seen that during rotation of the cylinder C, owing to the stud and groove connection between said cylinder and the rack bar R', the latter will be caused to reciprocate, and by means of the gear train A, A', A², A³, A⁴ and A⁵, such reciprocating motion is transmitted to the rack bar R. The vertical shaft A⁸ is preferably threaded through the gears A² and A³, as shown in Fig. 3 thereby to permit adjustment of said gears as to height, the gears being

keyed in their adjusted positions on the shaft. These gears may also be interchangeable thereby to permit the device to be used in the weaving of different widths of fabric. As illustrated herein, the rack 70 bar R carries at each end thereof a gripping device for engaging, cutting and laying the weft threads, as hereinafter explained. This gripping device is shown in detail in Figs. 7 to 12 and comprises a head G' formed at the end of rack bar R, said head being recessed at its outer end to receive the hinge or L-shaped end of an arm G⁶, which is pivoted in the recess of the head and has secured thereto a pinion G⁷, 80 said arm being adapted to be swung on its pivot from a position parallel with the head G' as shown in Figs. 7 and 12, to a position at right angles to said head as shown in Fig. 8. For cooperation with the pinion G⁷ to swing the arm G⁶, a rack bar G⁸ is disposed and guided in a longitudinal slot formed in the head G', as shown clearly in Figs. 7, 8 and 12, said rack bar being provided at its inner end with a lug G¹⁰, a coil spring G⁹ encircling the portion of the rack bar adjacent to said lug and being compressible between the lug and a shoulder formed at the junction of the head G' with the rack R, and which spring normally retains the arm G⁶ in parallel relation to the head G'.

Mounted for sliding movement longitudinally in the arm G⁶ is a plate or block G⁵, 90 the end of which extends somewhat beyond the end of the arm and which plate is provided with an elongated opening the top wall of which is inclined toward the free end of the arm to form a cam surface G¹⁶ for the purpose hereinafter described. The plate G⁵ is also provided at its inner end with a lug G¹² projecting therefrom for operating the plate as hereinafter described.

Supported on the arm G⁶ at right angles thereto is a lower gripping jaw G, the supporting or stem portion of which passes transversely through the elongated opening in the plate G⁵, and pivoted at G³ to said lower jaw is an upper jaw G² having a rearwardly extending portion or lever G⁴ which projects into said opening, the top surface of which lever is in contact with the edge of the top wall of the opening the arrangement being such that when the portion G⁴ is in the wider part of the opening the jaws will be closed together and when the plate G⁵ is moved inwardly toward the pivot of the arm G⁶, the inclined wall G¹⁶ of the opening will depress the jaw lever G⁴ and swing the upper jaw away from the lower jaw, thus opening the jaws. Attached to the lower jaw in parallelism therewith is a knife G¹⁴ which, when the jaws are closed together on a thread, will sever such thread.

Suitably disposed on the table N herein-

before described are two pair of stop members F and F', one pair for each loom, said members being preferably mounted for adjustment longitudinally of the table. In practice the outer stop F is pivotally mounted and is provided with a spring F² for returning the stop to its normal position when swung away therefrom. A stud F³ is threaded through the stop F and adapted to contact with the usual swinging batten D, which during its operation will swing the stop to the position shown in Fig. 5. The batten is indicated herein only in dotted lines because it is a well known member common in looms and forms no part of my invention. The stop member F' is similar to the member F except that it is not pivoted, since there is no necessity for changing its position.

The operation of the device is as follows: Assuming that the apparatus is about to start from its inoperative position indicated in Fig. 1. In this position the gripper arm G⁶ at each end of the rack bar R rests parallel with the head G', while the plate G⁵ is in its innermost position in the arm so that the inclined portion G¹⁶ of the wall of its opening is in engagement with the lever G⁴ of the upper jaw, so that the jaws are held open. Fig. 7 illustrates in plan view the relative position of the parts of the gripper at this time. Now, upon rotation of the cylinder C in the proper direction, the lead groove T therein will track the stud S toward the right, thus causing the rack bar R' to move toward the right, and by means of the gearing A, A', A², A³, A⁴ and A⁵ the rack bar R will also be moved toward the right, the open gripper jaws at the right hand end of the rack bar passing through the shed until it arrives beyond the right hand edge of the fabric being woven. On arrival at this point the open jaws G and G² will straddle the right hand end of the weft thread W between the fabric and the bobbin, as shown in Fig. 12. At this point, however, the lug G¹² of the plate G⁵ has come into contact with the stop F or a lug G¹³ carried thereby, so that as the rack bar R continues to move to the right the plate is caused to slide in the arm G⁶, thus carrying the wide portion of its opening into alignment with the jaws and permitting the latter to close on the thread, whereupon the knife G¹⁴ severs the thread while the jaws G, G² grip the loose end of said thread. The movement of the rack bar R to the right is completed just as the thread is severed. In the meantime the stud S has passed from the right lead groove T into the groove T' at the right hand end of the cylinder, thus permitting a certain "dwell" while the thread is being cut and gripped, whereupon the stud enters the left lead groove and the travel of the rack bar R toward the left

commences. The travel of the gripper mechanism toward the left is illustrated in Figs. 7, 8 and 12. At this time owing to the action of the eccentric B hereinbefore described, the bracket B² is caused to swing backward on its pivot just as the rack bar commences its return or left hand movement so as to carry the rack bar R and the gripper mechanism into approximately the position shown in dotted lines in Fig. 12 with relation to the fabric. During all of this time the arm G⁶ has remained parallel with the head G'. As the rack bar R approaches the limit of its left hand motion, however, the lug G¹⁰ at the inner end of the arm operating rack G⁸ comes into contact with a lug G¹¹ (see Figs. 7 and 8) carried by the stop member F', so that upon continued movement of the rack bar R toward the left the arm operating rack G⁸ is held against movement with the head G' and thus rotates the pinion G⁷, causing the arm G⁶ to swing away from the head into the position shown in Fig. 8, the spring G⁹ being in the meantime compressed between the lug G¹⁰ and the head G'. This swinging action of the arm occurs as soon as the jaws carrying the end of the weft thread have arrived at the left hand edge of the fabric. In other words, as soon as the closed jaws arrive in a position slightly left of the last warp thread of the fabric, there is no further movement of the jaws toward the left, although the head G' continues its movement, because at that time the lug G¹⁰ has come into contact with the lug G¹¹ of stop member F' and the swinging movement of the arm G⁶ has commenced, so that at the end of the movement of the rack bar R toward the left the jaws are approximately in the position shown in Fig. 8 with relation to the fabric, the eccentric B² having in the meantime swung the bracket B back to its normal position thus causing the jaws to place the weft thread in approximate parallelism with the threads previously laid. At the moment when the arm G⁶ arrives in a position at right angles with the head G', the outer end G¹⁵ of the plate G⁵ contacts with a cam surface G¹⁷ disposed on any convenient portion of the frame of the loom, as indicated in Fig. 8, which contact causes the plate G⁵ to slide inward in the arm G⁶, thus causing the inclined cam portion or wall G¹⁶ to engage the jaw lever G⁴ and open the jaws thereby to release the weft thread. At this time the stud S has entered the annular groove T' at the left of the cylinder and during the dwell thus caused the usual batten operates to press the thread back into its proper position in the fabric. By the time this has been accomplished, the stud is again entering the right hand lead groove T, whereupon the mechanism again begins its movement toward the right, and as the rack bar starts to move toward the right, the ten-

sion of spring G^9 exerts itself on the arm-operating rack G^8 and causes it to withdraw within the head G' , thus rotating the pinion G^7 and swinging the arm G^6 back into parallelism with the head G' , the jaws G, G^2 remaining open while the mechanism travels towards the right in the manner above described.

The operation above described takes into consideration only one loom. Where the device is used in connection with two looms, as shown herein, the above described motions of the gripping mechanism take place in reverse sequence in connection with the respective looms. In other words, when the gripping device at one end of the rack bar is carrying a thread from the outer toward the inner edge of the fabric in one loom, the gripping device at the opposite end of the rack bar is travelling empty from the inner toward the outer edge of the fabric in the other loom, and vice versa.

What I claim is:—

1. The combination with a loom, of a traversing member movable to and fro across the running board of the loom, means carried by said member for automatically gripping, and cutting a thread and carrying the same across the running board of the loom, and means for operating said traversing member.
2. The combination with a loom, of a weft-traversing motion comprising a cylinder mounted for rotation, a reciprocable rack disposed adjacent to said cylinder, cooperating means carried by the cylinder and rack for reciprocating the latter in response to the rotation of the cylinder, a second reciprocable rack adapted to move to and fro across the running board of the loom, means between said racks for transmitting motion from the first rack to the second, and means carried by said second rack for automatically gripping, carrying and releasing a weft.
3. The combination with a loom, of a weft-traversing motion comprising a cylinder mounted for rotation adjacent to said loom, a bracket mounted for pivotal movement about the axis of said cylinder, a reciprocable rack carried by said bracket and

disposed adjacent to the cylinder, cooperating means carried by the cylinder and rack for reciprocating the latter in response to the rotation of the cylinder, a second reciprocable rack adapted to move to and fro across the running board of the loom, means between said racks for transmitting motion from the first rack to the second, and means for rocking said bracket on its pivot thereby to carry said racks toward and away from the loom at predetermined points in the reciprocal movement of the racks.

4. The combination with a pair of looms, of a weft-traversing motion comprising a cylinder disposed between said looms and mounted for rotation, a reciprocable rack disposed adjacent to said cylinder, cooperating means carried by the cylinder and rack for reciprocating the latter in response to the rotation of the cylinder, a second reciprocable rack adapted to move to and fro across the running boards of both of said looms, means between said racks for transmitting motion from the first rack to the second, and means at each end of said second rack for automatically gripping, carrying and releasing a weft for each of said looms.

5. The combination with a pair of looms, of a weft-traversing motion comprising a cylinder disposed between said looms and mounted for rotation, a reciprocable rack disposed adjacent to said cylinder, cooperating means carried by the cylinder and rack for reciprocating the latter in response to the rotation of the cylinder, a second reciprocable rack adapted to move to and fro across the running boards of both of said looms, means between said racks for transmitting motion from the first rack to the second, means at each end of said second rack for automatically gripping, carrying and releasing a weft for each of said looms, and stops disposed in the path of movement of said gripping members for operating the same.

In testimony whereof I have signed my name to this specification.

EDGAR KILNER.
